UNITED STATES PATENT OFFICE.

ALBERT E. LANDZETTEL, OF PITTSBURGH, PENNSYLVANIA.

AMUSEMENT DEVICE.

Application filed June 3, 1921. Serial No. 474,723.

To all whom it may concern:

Be it known that I, ALBERT E. LANDZETTEL, a citizen of the United States, residing at Pittsburgh, in the county of Allegheny and State of Pennsylvania, have invented 5 certain new and useful Improvements in Amusement Devices, of which the following is a specification.

This invention relates to juvenile amusement devices and more particularly to foot sleds used by children on ice or snow covered paths in a similar manner as the now commonly called "scooters" are used by them on smooth concrete or asphalt courses. One 10 of the principal objects of this invention is to provide a device which is of simple operation and which can be manufactured at small cost. A further object is to provide a foot sled which is resiliently mounted on 15 runners. Still a further object is to provide such an amusement device of a foldable construction for the purpose of enabling the crating or storing of a number of such devices in the minimum space, thus reducing 20 the cost of freight or storage.

Referring to the drawings:

Fig. 1 represents a perspective view of the simplest construction of my single runner foot sled.

Fig. 2 is a side elevation of a modified construction of the foot sled provided with a foldable standard shown in its erected and folded position.

Fig. 3 is a front elevation corresponding 35 to Figure 2.

Fig. 4 is an enlarged side elevation of the type of runner shown in Figure 2.

Fig. 5 is a modified construction of the runner of the semi-resilient type and adapted 40 to be used in foot sleds with fixed standard as illustrated in Figure 1.

Fig. 6 is a cross-section through the runner taken along line 6—6 on Figure 5.

The most simplified construction of my 45 foot sled shown in Figure 1 consists of a foot plate 1, provided at the forward end with the suitably shaped standard 2 secured thereon by means of the corner plate 3 and the screws or bolts 4. The lower part of the 50 standard is usually made of equal width as the foot plate 1, whereas the upper part is suitably reduced to give to the sled a more pleasing appearance and also to reduce the weight thereof. The top of the standard is 55 provided with a fixed handle bar 5 of adequate size and shape for the purpose of pro-

viding means for the user to hold and balance himself on the foot sled. In order to reduce the cost of manufacture of the foot sled, the foot plates, standard and handle bar 60 are usually made of wood; but it is understood that any other material could be used if found desirable. The parts so far mentioned forming what might be called superstructure of the sled are mounted on the 65 metallic runner 6 of circular cross-section which in Figure 1 is shown to be of the full resilient type because of the peculiar formation of the two ends by which it is secured to the foot plate and standard. As will be 70 seen from Figure 1, the loop 7 and the cantilever arm 8 can be so dimensioned and shaped as to act as resilient supports for my foot sled for the purpose of reducing 75 to a minimum the shocks caused by asperities encountered on the roads or tracks upon which the sled is used.

The construction of the foot sled shown in Figures 2 and 3 differs from the one already described in that the standard 8 is 80 hingedly mounted upon the foot plate 9 by means of the butterfly hinge 10, the wings of which are respectively secured on the foot plate and the standard. The standard is held rigidly in its vertical position by means 85 of the corner stays 11 the lower ends of which are rockably mounted on the sides of the foot plate around the fulcrum pins 12 and the upper end of which are secured to the standard by means of a removable 90 pin 13 inserted through suitable apertures provided in said stays and in a substantially U-shaped bracket 14 made of a strip of metal and securely mounted upon the outer face of standard 8. Owing to the fact that the 95 standard is hingedly mounted, it will be noted that the construction of the full resilient runner 15 differs from the one described when referring to Figure 1. The difference 100 consists in that the forward loop 16 of the runner is carried underneath the foot plate 9 and secured thereto by suitable bolts or screws 17. For the purpose of providing means to securely hold the standard when in the folded position indicated in dot and 105 dash lines in Figure 2, I provide on the standard the additional bracket 14^a suitably positioned above the bracket 14. To fold the standard, it is only necessary to extract the pin 13 from the bracket 14 and corner 110 stays 11, and the standard will then fold down upon the foot plate 9 in which posi-

tion it can be securely held by inserting the pin 13 through the backwardly folded corner stays 11 and the bracket 14^a.

As already stated the method of operating the foot sled is analogous to that used with "scooters" and is as follows:

The user stands with one foot upon the foot board, balances himself thereon by means of the handle bar and propels the sled by applying the other foot to the ground and pushing forward. The smoothness of running will be enhanced by the resilient mounting of the sled upon the runners which greatly absorbs the shocks produced by whatever obstacles which may be encountered on the path.

While I have illustrated and described herein the preferred constructions of my invention, which I have found by actual use to be very practical, it may be found desirable, after continued experience, to make slight changes in the construction and arrangement of the details of my invention, and I intend to include in this application all such variations as fall within the scope of the appended claims.

What I claim is:

1. A foot sled of the character described, comprising a resilient runner of circular

cross-section; a foot board mounted substantially horizontally thereon; a standard hingedly mounted at the forward end of said foot board; a handle bar mounted transversely at the top of said standard and means for holding said standard into operating position.

2. A foot sled of the character described, comprising a resilient runner of circular cross-section; a foot board mounted substantially horizontally thereon; a standard hingedly mounted at the forward end of said foot board; a handle bar mounted transversely at the top of said standard and means for holding said standard into folded position.

3. A foot sled of the character described, comprising a resilient runner of circular cross-section; a foot board mounted substantially horizontally thereon; a standard hingedly mounted at the forward end of said foot board; a handle bar mounted transversely at the top of said standard and means for selectively holding said standard into either operating or folded position.

In testimony whereof I affix my signature.

ALBERT E. LANDZETTEL.
